CLAIM

The ornamental design for a table, as shown and described.

DESCRIPTION

FIG. 1 is a front perspective view of a table, showing our new design;

FIG. 2 is a front perspective view, showing the drawer in open condition;

FIG. 3 is a top plan view;

FIG. 4 is a bottom plan view;

FIG. 5 is a front elevational view;

FIG. 6 is a rear elevational view;

FIG. 7 is a left side elevational view; and,

FIG. 8 is a right side elevational view thereof.

The broken lines are for environmental purposes only and form no part of the claimed design.
